Specification for Design.

Patented Oct. 2, 1917.

Application filed July 3, 1917. Serial No. 178,481. Term of patent 7 years.

To all whom it may concern:

Be it known that I, SAMUEL A. WELLER, a citizen of the United States, residing at Zanesville, in the county of Muskingum and State of Ohio, have invented a new, original, and ornamental Design for Flag-Holders, of which the following is a specification, reference being had to the accompanying drawing, forming a part thereof.

Copies of this patent may be obtained for five cents each, by addressing the "Commissioner of Patents, Washington, D. C."

Fig. 2 is a rear elevation; and
Fig. 3 is a side elevation.

I claim:

The ornamental design for a flag holder, as shown.

SAMUEL A. WELLER.
